Attorney

UNITED STATES PATENT OFFICE.

MANES E. FULD, OF BALTIMORE, MARYLAND.

CATHODE.

Application filed September 21, 1920. Serial No. 411,302.

To all whom it may concern:

Be it known that I, MANES E. FULD, a citizen of the United States, residing at Baltimore, State of Maryland, have invented certain new and useful Improvements in Cathodes; and I do hereby declare the following to be a full, clear, and exact description of the invention, such as will enable others skilled in the art to which it appertains to make and use the same.

My invention relates to cathodes for battery cells.

One object of my invention is to provide a cathode for a battery cell comprising a conducting wire having a depolarizing material in electric connection therewith, and a wrapping of fibrous material bound around said depolarizing material by a conducting filament in such manner as to retain the wrapping in close contact with the depolarizing material, without establishing a path of lower resistance between said filament and the anode of the battery with which my improved cathode is used, than the paths between the other portions of my improved cathode and said anode.

In carrying out my invention, I make use of the instrumentalities illustrated in the accompanying drawings, in which:—

Fig. 1 is a sectional view of a cell, showing my improved cathode therein.

Fig. 2 is a perspective view of my improved cathode.

Fig. 3 is an enlarged partial longitudinal section of the bottom portion of my improved cathode.

In the drawings:—

My improved cathode 14 comprises a cathodic conductor 15 which, in my preferred form of cathode, is composed of silver. A cylinder 16, composed of chloride of silver which serves as a depolarizer, is cast around the lower portion of the cathodic conductor 15. The cylinder 16 does not extend to the lower end of the cathodic conductor 15, but a small portion 17 of said conductor extends below said cylinder for a purpose hereinafter explained. The cylinder 16 is provided with a spiral groove 18, cast or otherwise formed in the cylindrical surface thereof.

The wrapping 19 is placed over the cylinder 16 and the ends of said wrapping are

folded over the ends of said cylinder as at 20 and 21. The filament 22, which in my preferred form of cathode is a fine silver wire, has one end wound around the conductor 15 adjacent to the upper end of the cylinder 16, as at 23, said filament is then wound around the wrapping 19 and presses said wrapping into the groove 18; the other end of the filament 22 is then wrapped around the portion 17 of the conductor 15, as at 24.

When the filament 22 is wound around the wrapping 19, it presses said wrapping into the groove 18 until the outer surface of said filament is at approximately the same, or a less, distance from the axis of the cylinder 16 than the distance of the cylindrical surface of said wrapping from said axis.

Where the ends of the filament are carried across the wrapping at the ends of the cylinder, as at 20 and 21, and wound around the conductor 15, as at 23 and 24, said ends of the filament serve to secure the folded over ends of the wrapping 19.

The fibrous wrapping 19 serves to hold any particles that might break away from the chloride of silver cylinder 16 and also prevents the short circuiting of the battery which might otherwise take place by the formation of a bridge of metallic particles between the cathode and the anode.

I have shown one embodiment of my improved cathode, but it is evident that many changes may be made therein without departing from the spirit thereof.

I claim:—

As a new article of manufacture, a cathode comprising a conductor, a cylinder of depolarizing material molded around said conductor and formed with a spiral groove extending throughout the length of said cylinder, a fibrous wrapper around said cylinder and folded over the ends thereof and a wire connected at one end to said conductor passing over the folded end of said paper and around said wrapper pressing it into said groove, then over the folded end of said wrapper and having its other end connected to said conductor.

In testimony whereof, I affix my signature.

MANES E. FULD.
